UNITED STATES PATENT OFFICE

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY

FASTENING INSERTING MACHINE

Application filed January 21, 1931. Serial No. 510,230.

This invention relates to mechanisms for controlling the lengths of fastenings in accordance with the thickness of the work in which they are inserted and is illustrated herein as embodied in a staple lasting machine.

Not only do work pieces which are secured together by fastenings vary in thickness but it has been found that frequently there is a substantial variation in thickness between different portions of the same work piece. Accordingly, it is desirable and in some cases necessary to vary the length of each fastening in accordance with the thickness of the work into which the fastening is to be inserted.

In view of the above, it is an object of the present invention to provide improved means for automatically controlling the length of each fastening in accordance with the thickness of the work piece into which the fastening is to be inserted.

The illustrated machine, which includes a preferred embodiment of my invention, is of the general type disclosed in Letters Patent of the United States No. 1,291,754, granted January 21, 1919 on an application filed in the name of Matthias Brock, and is provided with a work support which is raised to clamp the work against an abutment during the fastening inserting operation and is then lowered to permit the work to be removed. Wire feeding and severing mechanism is provided mounted on a carrier which is adapted to be moved toward and from the staple forming instrumentalities of the machine to cause the severing mechanism to cut off pieces of wire of different lengths and thereby to vary the lengths of the staples which are formed. The extent of movement of the wire feeding mechanism is governed by the position of said carrier relatively to the staple formers so that said feeding mechanism will feed the wire varying distances to cause the center of the severed pieces of wire to rest upon the inside former which comprises one of the staple forming instrumentalities. Preferably and as shown, the carrier on which is mounted the wire feeding and severing mechanism is moved toward the staple forming instrumen-

talities of the machine as the work support is moved into work clamping position and is yieldingly moved away from said forming instrumentalities as the work support is lowered. As illustrated, and in accordance with 55 a feature of my invention, the means for moving the carrier toward the staple forming instrumentalities as the work support is moved into work clamping position includes a bell crank lever arranged to cooperate with an adjustable member carried by the work support to insure the correct positioning of the carrier relatively to the staple forming instrumentalities in accordance with the thickness of a work piece. The bell crank lever is pivoted 60 in the head of the machine and is provided with an upwardly extending arm connected to the carrier and a laterally extending arm which lies in the path of movement of the adjustable member carried by the work support, the construction and arrangement being such that as the work support is moved upwardly to clamp the work the bell crank lever is rocked through a greater or less angle according to the position of the work support 76 75 to control the length of a fastening.

With the above and other objects and features in view the invention will now be described in connection with the accompanying drawings and pointed out in the claims. 80

In the drawings,

Fig. 1 is a side elevation of a fastening inserting machine embodying the present invention;

Fig. 2 is a front elevation of the head of the 85 machine shown in Fig. 1; and

Fig. 3 is an elevation on an enlarged scale partly in section taken on the line III—III of Fig. 1 looking toward the front of the machine. 90

The illustrated machine is provided with staple forming and inserting mechanism which is operative to insert fastenings in a work piece maintained upon a work support which is raised to clamp the work against an abutment during the fastening inserting operation, the said staple forming and inserting mechanism being preferably, though not necessarily, of the type disclosed in Letters Patent of the United States No. 1,016,930, 95 100

granted Feb. 13, 1912 on an application of W. H. Borden. The illustrated machine is provided with a base 10 to which is secured a head 12 and a work support 14. The head 12 carries a cam shaft 16 from which various parts of the machine are operated. A driver bar 20 carrying a driver 22 is moved upwardly by means of a lifting cam 24 which engages a block 26 carried by the driver bar 20. A spring 28 anchored at one end to a stationary part of the head of the machine and connected at the other end by a link 30 with the driver bar 20 forces the driver bar 20 and driver 22 downwardly as the cam 24 passes out from under the block 26, thus driving a fastening into the work, and is compressed as the cam 24 lifts the driver bar 20. The work support 14 is of the type disclosed in Letters Patent of the United States No. 1,291,754, granted January 21, 1919 on an application filed in the name of Matthias Brock, and is operated directly from a treadle 32 and also by power means including a cam 34 on the cam shaft 16 and connections to wedges one of which is shown at 36 in Fig. 1, arranged to operate upon rolls 38 carried by the work support 14 in the manner fully disclosed in said patent to Brock.

The wire 40 which forms the staples is fed to the staple forming mechanism from a reel 42 by means of a feed roll 44 in substantially the same manner as in the machine shown in Patent No. 1,016,930 to W. H. Borden, and is cut by cutting mechanism of substantially the same construction as in the machine shown in said Letters Patent to W. H. Borden. The release of the wire for the return movement of the feed roll 44 is effected during the cutting operation by the action of a plunger 46 which engages an adjustable stop 48 on a lever 50 which carries a co-operating presser roll. In order that staples of different lengths may be formed the wire severing mechanism is mounted on a carrier 54 which is movable horizontally toward and from the staple forming instrumentalities of the machine and for insuring that both legs of the staple will be of the same length the degree of movement of the wire feeding mechanism is governed by the position of the carrier 54 relatively to the staple forming instrumentalities so that the wire will be fed varying distances to cause the center of the severed piece of wire to rest upon the inside former. The carrier 54 is slidably mounted on stationary rods 56, 58 (Fig. 1) fastened to the head 12 of the machine and when said carrier is moved to the left, as viewed in Fig. 2, the cutting mechanism will be carried away from the inside former and a longer piece of wire will be cut, the degree of movement of the feeding mechanism being simultaneously automatically increased to feed more wire so that the center of the severed piece of wire will rest upon the inside

former and thus insure both legs of the staple being of the same length. When the carrier 54 is moved to the right, as viewed in Fig. 2, the severing mechanism will be brought nearer to the inside former and a shorter piece of wire will be cut, the degree of movement of the wire feeding mechanism being simultaneously automatically decreased to feed less wire. The feed roll 44 is mounted on the end of an oscillating shaft 60 (Fig. 2) supported in the carrier 54 and operated by means of a lever 62 fulcrumed on a stud 64 on the carrier 54 and having at its lower end a segment 66 which meshes with a gear 68 fastened to the feed roll shaft. The lever 62 is provided at its upper end with a slot 70 which receives a roll 72 fastened to an arm 74 and is connected to a rock shaft 76 mounted in bearings 78 on the head of the machine and fastened to said shaft is a second arm 80 provided with a roll 82 which travels in a groove 84 in the cam block 85.

The severing mechanism comprises a stationary cutter 86 fastened to the carrier 54 by a clamping plate 88 and a movable cutter 90 fastened by a clamp 92 to a cutter carrier bar 94 which is provided with a hook-shaped end 96 to engage an L-shaped piece 98 on an actuator bar 100. The actuator bar 100 is slidably mounted in a guideway in the head of the machine and is provided with rolls 102, 102 which co-operate with a cam 104 on the cam shaft 16. Rotation of the cam 104 is operative to move the actuator bar 100 and consequently the cutter bar positively in both directions, the connections between the actuator bar and the cutter bar being such that the cutter bar is permitted to move laterally with the carrier 54 in which it is mounted.

From the foregoing it will be readily seen that since the rock shaft 76 is mounted in the head of the machine the extent of movement of the arm 74 will be uniform with each cycle of operations of the machine and, as the lever 62 is fulcrumed on the carrier 54, movement of said carrier toward and from the staple forming and inserting instrumentalities of the machine will change the relation of the stud 64 to the path of movement of the roller 72. Consequently, the degree of movement of the arm 62 and the feed roll 44 will vary in accordance with the position of the carrier 54 so that the wire will be fed for varying distances to cause the center of the severed piece of wire to rest upon the inside former of the machine. The details of the mechanism thus far described for feeding and cutting the wire are similar to those disclosed in the Letters Patent No. 1,016,930 to W. H. Borden, to which patent reference may be had for more detailed description of the wire feeding and cutting mechanism.

Automatic means is provided in the illustrated construction for controlling the length

of the fastening formed in accordance with the thickness of the work into which the fastening is to be inserted. As shown, the work support 14 is provided with a work supporting post 106 to the upper end of which is secured an anvil 108 on which the work may be sustained during the fastening inserting operation. The post 106 is provided with a rearwardly extending arm 110 carrying an adjustable set screw 112. The set screw 112 may be held in adjustable position by means of a binding screw 114. The head 12 of the machine is provided with a downwardly extending portion 116 carrying a shaft 118 to one end of which is secured a bell crank lever 120 having a laterally extending arm 122 carrying at its outer end a stud 124 the head 126 of which lies in the path of movement of the set screw 112 when the work supporting post 106 is moved upwardly to clamp the work. Secured to the other end of the shaft 118 is a lever 128 (Fig. 3) through the outer end of which passes a rod 130 pivotally connected to a lever for operating the wedge 36 and carrying a spring 132 which tends to move the lever 128 and bell crank lever 120 in a counterclockwise direction, as viewed in Fig. 2. The bell crank lever 120 has an upwardly extending arm 134 having teeth 136 formed thereon arranged to engage teeth formed on a rack bar 138 secured to the carrier 54.

In operation the treadle 32 is depressed by the operator to raise the work supporting post 106 and anvil 108 toward the fastening inserting mechanism to clamp the work against an opposed abutment, which in the illustrated machine comprises a nozzle 140, after which a starting treadle 142 may be depressed to set the fastening inserting mechanism and work support locking mechanism in operation. Upward movement of the work supporting post 106 causes the set screw 112 to engage the head 126 of the stud 124 and to move the bell crank lever 120 in a clockwise direction, as viewed in Fig. 2, against the action of the spring 132. Movement of the lever 120 in a clockwise direction causes the carrier 54 to move to the right an amount determined by the angle through which the lever 120 is rocked as the work support is moved into work clamping position. The set screw 112 may be adjusted relatively to the arm 110 so that more or less rocking movement may be imparted to the lever 120. Thus, it will be readily seen that by automatically moving the carrier 54 into predetermined relation to the staple forming and inserting instrumentalities of the machine as the work support is moved into work clamping position, the length of a fastening formed may be accurately controlled in accordance with the thickness of a work piece.

Having described the invention, what I

claim as new and desire to secure by Letters Patent of the United States is:

1. A fastening inserting machine having, in combination, staple forming instrumentalities, a carrier provided with wire feeding and severing mechanism, said carrier being movable toward and from said forming instrumentalities to cause the severing mechanism to cut pieces of wire of varying lengths, means controlled by the position of the carrier to determine the extent of the feeding movement of the wire, a work support movable from a work receiving to a work clamping position, means for positively moving said carrier toward the staple forming instrumentalities as the work support is moved into work clamping position to control the length of a fastening, and means for yieldingly moving said carrier away from said forming instrumentalities as the work support is lowered.

2. A fastening inserting machine having, in combination, staple forming instrumentalities, a carrier provided with wire feeding and severing mechanism, said carrier being movable toward and from said forming instrumentalities to cause the severing mechanism to cut pieces of wire of varying lengths, means controlled by the position of the carrier to determine the extent of the feeding movement of the wire, a work support movable from a work receiving to a work clamping position, a bell crank lever connected to said carrier and arranged by its rocking movement to shift the carrier, and means carried by the work support and arranged to rock the bell crank lever through an angle determined by the position to which the work support is moved to clamp the work whereby the thickness of the work controls the length of the piece of wire to be severed.

3. A fastening inserting machine having, in combination, staple forming instrumentalities, a carrier provided with wire feeding and severing mechanism, said carrier being movable toward and from said forming instrumentalities to cause the severing mechanism to cut pieces of wire of varying lengths, means controlled by the position of the carrier to determine the extent of the feeding movement of the wire, a work support movable from a work receiving to a work clamping position, a bell crank lever connected to said carrier, and means carried by the work support and arranged to cooperate with the bell crank lever to move the carrier toward the staple forming instrumentalities as the work support is moved into work clamping position thereby controlling the length of the fastening inserted.

4. A fastening inserting machine having, in combination, staple forming instrumentalities, a carrier provided with wire feeding and severing mechanism, said carrier being movable toward and from said forming in-

strumentalities to cause the severing mechanism to cut pieces of wire of varying lengths, means controlled by the position of the carrier to determine the extent of the feeding movement of the wire, a work support movable from a work receiving to a work clamping position, a bell crank lever connected to said carrier, and adjustable means carried by the work support and arranged to cooperate with the bell crank lever to determine the position of the carrier relatively to the staple forming instrumentalities to control the length of the fastenings.

5. A fastening inserting machine having, in combination, staple forming instrumentalities, a carrier provided with wire feeding and severing mechanism, said carrier being movable toward and from said forming instrumentalities to cause the severing mechanism to cut pieces of wire of varying lengths, means controlled by the position of the carrier to determine the extent of the feeding movement of the wire, a work support movable from a work receiving to a work clamping position, a bell crank lever connected to said carrier, a member carried by the work support and arranged to rock the bell crank lever through a greater or less angle as the work support is moved into work clamping position thereby to control the length of the fastenings inserted, and means for holding the bell crank lever in engagement with the member during its rocking movement.

6. A fastening inserting machine having, in combination, staple forming instrumentalities, a carrier provided with wire feeding and severing mechanism, said carrier being movable toward and from said forming instrumentalities to cause the severing mechanism to cut pieces of wire of varying lengths, means controlled by the position of the carrier to determine the extent of the feeding movement of the wire, a rack bar secured to said carrier, a bell crank lever having teeth formed thereon meshing with said rack bar, a work support movable from work receiving to work clamping position, and adjustable means carried by said work support and arranged as the work support is moved into work clamping position to rock said bell crank lever about its fulcrum to move said carrier toward the staple forming means thereby controlling the length of each fastening in accordance with the thickness of the work.

7. A fastening inserting machine having, in combination, staple forming instrumentalities, a carrier provided with wire feeding and severing mechanism, said carrier being movable toward and from said forming instrumentalities to cause the severing mechanism to cut pieces of wire of varying lengths, means controlled by the position of said carrier to determine the extent of the feeding movement of the wire, a rack bar secured

to said carrier, a work support movable from work receiving to work clamping position, and a bell crank lever having an upwardly extending arm having teeth formed thereon meshing with said rack bar, said bell crank lever having a laterally extending arm which lies in the path of movement of said work support whereby the movement of said work support into work clamping position is effective to rock said bell crank lever through a greater or less angle to control the length of the fastenings.

8. A fastening inserting machine having, in combination, staple forming instrumentalities, a carrier provided with wire feeding and severing mechanism, said carrier being movable toward and from said forming instrumentalities to cause the severing mechanism to cut pieces of wire of varying lengths, means controlled by the position of the carrier to determine the extent of the feeding movement of the wire, a rack bar secured to said carrier, a work support movable from work receiving to work clamping position, a bell crank lever having an upwardly extending arm having teeth formed thereon meshing with said rack bar, said bell crank lever having a laterally extending arm which lies in the path of movement of said work support whereby movement of said work support into work clamping position is effective to rock said bell crank lever about its fulcrum to move said carrier toward the staple forming instrumentalities of the machine to control the length of each fastening in accordance with the thickness of the work, and means carried by said work support and adjustable relatively thereto to vary the extent of rocking movement imparted to said bell crank lever.

In testimony whereof I have signed my name to this specification.

FRED L. MACKENZIE.
